UNITED STATES PATENT OFFICE.

FRANCIS F. LUCAS, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE PLUG SHELF.

Application filed April 24, 1920. Serial No. 376,257.

To all whom it may concern:

Be it known that I, FRANCIS F. LUCAS, a citizen of the United States, residing at East Orange, in the county of Essex, State 5 of New Jersey, have invented certain new and useful Improvements in Telephone Plug Shelves, of which the following is a full, clear, concise, and exact description.

This invention relates to plug shelves for 10 telephone manual switchboards.

It has for an object to provide a shelf which will absorb the shocks which ensue in service to the plugs, plug shells and cords when these parts are restored to their non- 15 operative positions in the plug shelf.

Another object is to reduce the wear and abrasion of the switchboard cord.

In the sheet of drawings accompanying this specification, Fig. 1 shows an end view 20 of a manual telephone switchboard; Fig. 2 is a cross-sectional view of the improved plug shelf; Fig. 3 a plan view of the shelf as constructed according to this invention; and Figs. 4 and 5 show a modification of 25 the invention.

In Fig. 1, the switchboard 1 is represented in end view with the plug shelf 2 and one set of plugs 3 and 6 together with their respective cords 4 and 7 and their restoring 30 cord weights 5 and 8. Plug 6 which, being situated nearest the board, is generally referred to as the answering plug, is shown inserted in the board in its operative position. Plug 3, the calling plug, is in its non- 35 operative position, being held in position by its cord weight 5. The usual construction of the plug shelf 2 has heretofore quite generally been of a hard maple base faced with semi-hard rubber. Upon returning a plug 40 from its operative position to its non-operative position the operator removes the plug from the jack in which it has been inserted and then allows the cord weight to restore the plug to the plug shelf. Before the plug 45 finally comes to rest it goes through a series of motions due to the shifting of the center of gravity of the combination of the plug and cord and cord weight and also to the restraining influence which the plug shelf 50 exerts on the cord as it passes through the cylindrical opening therein. At first the plug assumes a horizontal position, the tip pointing, for example, toward the left. The tip then strikes the base of the plug shelf 55 from which it bounds and with a whip ac-

tion travels upward and over toward the right. The plug by this time acquires a relatively high velocity and continues in this state until it reaches a position somewhat similar to that shown in Fig. 2. At this 60 point the travel is suddenly arrested and a rebound occurs, which is terminated when the plug is in a somewhat similar position to that shown in Fig. 2, leaning, however, toward the left. Finally the plug reaches 65 its seat and assumes a vertical position, such as that shown by plug 3 in Fig. 1. It will be clear that during these operations the plug tends to become wedged against the wall of the cylindrical opening in the plug shelf 70 and from the motion imparted the tendency is to bend the plug over the rim of the plug shelf hole. That is, there is a resultant of forces which operates to break the plug and the plug shell much in the same manner as 75 a small piece of wood might be broken over the knee. It will also be apparent that the base of the plug will gouge the wall of the plug shelf opening. This produces a rough, splintery surface by which the cord is 80 abraided. The bends imparted to the cord just below the base of the plug also tend to destroy the cord. This bending of the cord takes place at least four times during the restoration of the plug to its non-operative 85 position.

In accordance with the present invention, a plug shelf is provided which will absorb the shocks of the plug and associated parts and thus decrease the breakage of these 90 parts correspondingly. The surface of the plug shelf is, in accordance with the invention, made somewhat flexible and capable of moving slightly to prevent the tendency of the plug shelf to wedge therein. To lessen 95 the abrasion of the cord, a material of a softer and less fibrous and splintery nature than wood is provided.

Referring now to Figs. 2 and 3, which show more in detail the plug shelf as constructed in accordance with this invention, the semi-hard rubber facing 9 is secured by suitable means to a resilient material 10. It has been found that cork, which is a product from the stems and roots of 105 woody plants which increase in diameter year by year and more particularly derivable from the outer layer of the bark of the evergreen species of oak, *Quercus suker*, is well suited for the resilient layer. Sub- 110

stances such as cork, which have the power of altering their volume in a very marked degree in consequence of change of pressure, furnish a means by which the shocks 5 encountered in restoring plugs to their non-operative position, may be absorbed. Such materials possessing an aggregation of minute air vessels having thin and very strong walls, when compressed exhibit a 10 resistance of compression more like the resistance of gases than the resistance of an elastic material such as a spring. Sponge rubber, felt, linoleum, and the like, have properties which make them desirable for 15 use in this connection. Cork, however, appears to be superior to other materials in that in addition to its pressure resisting properties, it also resists abrasion to a marked degree and does not deteriorate 20 rapidly. Other properties of cork which make its use advantageous are its heat, combustion, and moisture resisting qualities. The wooden strip 11 is attached to the under surface of the resilient material to 25 which the base strip 12 is affixed. Cylindrical openings 13 and 15 for the plug and cords respectively are provided together with the plug seat 14.

As a modification of the above described 30 plug shelf, the cork insert shelf represented by Figs. 4 and 5 has been constructed. In this type of plug shelf a trough or slot 16 (Fig. 5), is provided through the portion of the shelf in which the plugs function. No 35 elastic medium between adjacent plug holes of the same row is provided, in order to do away with the thin wall of elastic material which might chip or break in service. This is considered to be desirable in cases where the plug holes are necessarily situated in close proximity to one another, as is the 40 case in some types of telephone switchboards. The cork inserts provide the necessary flexibility and because of the trough or slot construction, the base of the plugs 45 do not tend to wedge in the same manner as in the ordinary type of shelf. In Fig. 4, a plug shelf of the modified type is shown, 18 representing the number plate 50 aperture, which is commonly placed at the rear of the plug. The resilient layer is

in this case made up of two separate portions, the cylindrical opening 13 being formed by the projections of the wooden base 11.

55

As a result of comparative tests which have been made using the ordinary type of plug shelf and the one constructed in accordance with this invention, it was found that the plug shelf embodying the resilient 60 material showed no appreciable wear after 85,000 operations, whereas the ordinary type was badly worn after 70,000 operations.

From tests conducted utilizing a telephone 65 plug equipped with a fibre plug shell, it was apparent that, even under average service conditions, the cushion type of plug shelf will increase the life of both plug and shell approximately twelve times. Cords which showed failure after 30,000 operations 70 when used with the ordinary plug shelf were still in good condition after 85,000 operations when the cushion plug shelf was used.

75

While specific forms of construction are 75 shown herein, it is apparent that this invention may find application in other obvious modifications.

What is claimed is:

1. A laminated telephone plug shelf having 80 openings therein for the plugs, comprising an inner layer of cork.
2. A telephone plug shelf comprising a rubber-faced resilient material with openings therethrough for the plugs and cords. 85
3. A telephone plug shelf comprising rubber-faced cork having openings therein to receive the plugs.
4. A laminated telephone plug shelf comprising rubber, resilient material, and wood, 90 and having openings therethrough for the plugs.
5. A laminated telephone plug shelf composed of a base upon which the plugs rest, 95 a layer of resilient material, and an impact surface of semi-hard rubber; the base, resilient material and impact surface having coincident openings therethrough.

In witness whereof I hereunto subscribe my name this 20th day of April A. D., 1920. 100

FRANCIS F. LUCAS.
